UNITED STATES PATENT OFFICE.

OLIVER B. ANDREWS, OF CHATTANOOGA, TENNESSEE.

DISINFECTING-COOP.

1,217,677.

Specification of Letters Patent. Patented Feb. 27, 1917.

Application filed December 4, 1916. Serial No. 134,954.

To all whom it may concern:

Be it known that I, OLIVER B. ANDREWS, a citizen of the United States, residing at Chattanooga, in the county of Hamilton and State of Tennessee, have invented certain new and useful Improvements in Disinfecting-Coops; and I do hereby declare the following to be a full, clear, and exact description of the invention, such as will enable others skilled in the art to which it appertains to make and use the same.

This invention relates to disinfecting chicken coops or crates, and has for its object to provide a coop of this nature which will be simple in construction, efficient in action and comparatively inexpensive to manufacture.

With these objects in view the invention consists in the novel details of construction and combinations of parts more fully hereinafter disclosed and particularly pointed out in the claim.

Referring to the accompanying drawings forming a part of this specification in which like numerals designate like parts in all the views:—

Figure 1 is a sectional view illustrating a coop made in accordance with this invention;

Fig. 2 is a sectional detail view illustrating the construction of the bottom of the coop; and Fig. 3 is a sectional view showing a modified form of disinfectant holding receptacle.

1 represents a top portion of a coop preferably inclined as shown, 2 the rear thereof, 3 the front portion or door of said coop, 4 the bottom of said coop and 5 the sides thereof. Inside the said coop and resting on the bottom thereof are the two ledges or strips 6 and 7, and fitting on the inside of said ledges are the supports or strips 8 and 9 respectively to which a false bottom 10 is attached. The said strips 8 and 9 serve to hold the false bottom 10 firmly in place against the strips 6 and 7, and also to position said false bottom 10 at the proper predetermined distance above the bottom 4 and above the disinfectant receptacle 12.

The said strips 8 and 9 are provided with the V-shaped notches or openings 13 and the said false bottom is provided with the holes or perforations 14 as illustrated. The disinfecting material 16 is preferably held on

the interior of a middle receptacle 17 which is surrounded by the main receptacle 12 and said middle receptacle 13 is preferably provided with the notches or holes 18 in order to permit the powdered material 16 to escape into the annular space 19 between the said middle receptacle 17 and the surrounding flange of the receptacle 12, all as will be clear from the drawings.

As these coops or crates are adapted to be shipped it is very desirable that the false bottom 10 snugly fit the interior of the crate as shown and in order to better secure it in position the edges 20 of the false bottom extend over the ledges or strips 6 and 7 and contact with the surfaces 21 of the latter as illustrated. On the other hand, it is very desirable that the disinfecting vapors have a free passage from the space 22, containing the receptacle 12, into the space 23 of the coop proper. The holes 14 afford an escapement for said vapors but it is found desirable to cut away the edges 25 of said ledges 6 and 7, and thus permit a free passage of the said vapors through the holes 13 and the holes 14 with which the edges 20 are provided, all as will be clear from the drawings.

It thus results that notwithstanding the fact that the false bottom 10 fits snugly both the interior of the coop and the surfaces 21 of the ledges 6 and 7, and notwithstanding the fact that the strips 8 and 9 may fit snugly the inside surfaces of the said strips 6 and 7, yet a free access for the said vapors is had from the space 22 to the space 23.

In the modified form of receptacle shown in Fig. 3 it is of an inverted disk shape having the rising portion 30, the grooves or channels 31 and the flange portion 32. The interior receptacle 33 is provided with the holes 34 registering with the channels 31 and the construction is such that the disinfecting powder 16 may pass through said holes 34 through said channels 31 and reach the liquid 35 as will be clear from the drawings.

What I claim is:—

In a disinfecting chicken coop the combination of a main body portion provided with a bottom; a pair of strips secured to said bottom and the sides of said body portion; a false bottom having perforations located above and resting on said strips; a second

pair of strips secured to said false bottom fitting inside said first mentioned pair of strips and also provided with perforations, the inner upper edges of said first named strips being cutaway to afford a ready communication between the perforations of said second pair of strips and certain of the perforations in said false bottom; and a dis-

fectant holding receptacle located between said bottoms, substantially as described.

In testimony whereof I affix my signature, in presence of two witnesses.

OLIVER B. ANDREWS.
